TAPE DISPENSING DEVICE

Ernest Stanton King, Minneapolis, Minn.

Application April 19, 1952, Serial No. 283,212

5 Claims. (Cl. 164—84.5)

1

This invention relates to a dispensing device for use on a roll of material and more particularly on a roll of material such as a roll of adhesive tape. This invention relates to a device adapted to be disposed on a roll of tape and to remain on the periphery of said roll while tape is being dispensed from said roll through said device. It is particularly desirable to have a dispensing device adapted to be disposed on a roll of material, such as adhesive tape, whereby said roll of tape and said dispensing device can be held in operating position by one hand of the operator while tape is dispensed from said roll with the other hand of the operator.

It is therefore an object of this invention to provide a dispensing device to be used on a roll of adhesive tape and adapted to remain on the periphery of said roll while said tape is being dispensed from said roll through said device.

It is another object of this invention to provide a dispensing device to be used on a roll of adhesive tape whereby one hand of the operator can hold said roll of tape and said device thereon in operating position while tape is being dispensed through said device by the other hand of the operator.

It is still another object of this invention to provide a dispensing device to be used on a roll of tape comprising a member of sheet material having a top wall, side walls extending downwardly therefrom and adapted to be disposed along the sides of said roll of tape, said device having a spaced opening vertically therethrough and said tape from said roll being dispensed through said opening.

It is a further object of this invention to provide a dispensing device as set forth in the preceding paragraph, together with a means for cutting said tape from said roll when a desired amount has been dispensed from said roll.

It is a still further object of this invention to provide a dispensing device for use on a roll of tape comprising a member of sheet material having end and side walls at right angles to each other, said side walls being adapted to be disposed along the side of said roll, said end walls having opposite edge portions adapted to rest on the periphery of said roll and other edge portions spaced from each other to form an opening and one of said other edge portions forming a cutting edge.

It is also an object of this invention to provide a dispensing device for use on a roll of tape having superposed layers of material, such as a cover strip, overlying a layer of adhesive tape, said de-

2

vice comprising a member of sheet material having a top wall, side walls adapted to be disposed along the sides of said roll of tape, said side walls having end portions bent inwardly at right angles forming overlapping portions and one of said overlapping portions having a cutting edge formed along its upper edge portion, the lower edge portion of one of said overlapping portions and a portion of said top wall resting on the periphery of said roll, and spaced openings in the top portion of said device, said cover strip and said tape respectively being dispensed through said spaced openings.

These and other objects and advantages of the invention will be fully set forth in the following description made in connection with the accompanying drawings in which like reference characters refer to similar parts throughout the several views and in which—

- 20 Fig. 1 is a plan view of the device;
 Fig. 2 is a view in perspective;
 Fig. 3 is a view in side elevation of said device shown in operating position;
 Fig. 4 is a view in end elevation;
 25 Fig. 5 is a view in vertical section taken on line 5—5 of Fig. 4, as indicated by the arrows;
 Fig. 6 is a view in horizontal section taken on line 6—6 of Fig. 4, as indicated by the arrows;
 Fig. 7 is a view in perspective of a modification
 30 of the device;
 Fig. 8 is a view in perspective of another modification of the device;
 Fig. 9 is a view taken on line 9—9 of Fig. 8; and
 Fig. 10 is a view of the device in operating position with the hands of the operator shown in position to operate the same.

Referring to the drawings, a dispensing device 10 to be used on a roll of material is shown. Referring to Fig. 3, said device 10 is shown in operating position on a roll of material 11. Said roll of material 11 is here shown to be a roll of adhesive tape. Said device may be made of any suitable sheet material, and in the embodiment of the invention as illustrated, said device is shown as being made of sheet metal. Said device has a top end wall 10a having an outer edge portion 10p adapted to rest on the periphery of a roll of material and said end wall is inclined at an angle to extend tangentially from said roll. Said end wall has an end portion 10b which is reversely bent to be parallel to said end wall for a short distance and has an edge portion 10r inclined upwardly at a slight angle. Said portion 10b and edge portion 10r form a thumb rest. Extending downwardly from each side of member 10a are

side members 10c and 10d. Said side members 10c and 10d extend in parallel planes and are adapted to be disposed along the sides of the roll of tape upon which said device is disposed. Said side members 10c and 10d are of a substantial length and have end portions 10e and 10f bent inwardly at right angles thereto and thus forming overlapping end portions. Portion 10e has an outwardly extending upper edge portion 10g forming a cutting edge. In the embodiment of the device as illustrated, said cutting edge is shown to be a saw-tooth edge. Portion 10e also has a lower depending edge portion 10h bent outwardly at a slight angle and adapted to rest on the periphery of a roll of tape. Said overlapping portions 10e and 10f are secured together by a fastening means 12. In the embodiment of the invention as illustrated, said fastening means 12 is shown to be a rivet. Extending between members 10c and 10d and secured thereto adjacent the front edge portion of member 10e is a bar or rod 13. Disposed about said bar 13 is an elongated tubular roller 13a extending between said side members 10c and 10d and freely rotatable about said bar member 13. Intermediate the upper edge portions of said overlapping members 10e and 10f and the front edge portion of member 10a is a space extending vertically through said device.

In operation, said device is disposed on a roll 30 of tape and is supported thereon by the outer edge portion 10p of member 10a and said edge portion 10h. The side members 10c and 10d are respectively disposed along the sides of said roll of tape. End member 10a extends tangentially from said roll, as shown in Fig. 3. Referring to Fig. 10, the end portion 11a of a layer of tape is raised and is passed between members 10c and 10d upwardly through the space in said device 35 and is drawn outwardly. The roll of tape is held lightly in one hand and the ball of the thumb of the said hand is placed over portion 10b and pressed lightly downwardly. Said layer of tape is then pulled outwardly with the other hand of the operator. Thus the device is held in stationary position resting on the periphery of the roll of tape while said roll of tape is rotated in the hand of the operator as a layer of the same is being dispensed or drawn outwardly through said dispensing device. As said layer of tape is 40 pulled outwardly it moves against said roller 13a which rotates freely to facilitate the pulling of said layer of tape and said bar 13 holds said side members 10c and 10d in their spaced relation. When a desired length of tape has been pulled through said device, said tape is moved downwardly against said cutting edge 10g and is easily severed thereby.

A modification of the above described device is shown in Fig. 7. All parts as indicated by the same characters as used in Figs. 1-6 are of identical structure. In the present modification, a bar 14 extends between members 10c and 10d adjacent the rear edge portion 10p of member 10a. The ends of bar 14 are respectively secured in members 10c and 10d. Disposed about said bar and extending between said members is a tubular roller 14a freely rotatable about said bar.

The operation of the above modification is the same as described in the above operation with the exception of members 14 and 14a which are positioned in the modification so as to rest on the periphery of the roll of tape on which said device is disposed and said roller 14a will facilitate the movement of said roll of tape as the

periphery of the same moves through said device while the tape from said roll is being dispensed.

Another modification of the above described device is shown in Figs. 8 and 9. The structure shown in this modification is substantially the same as the structure shown in Figs. 1-6 and the same characters are used to show identical parts. In the present modification said end portion 10a is somewhat modified and is here shown as member 10j. Said member 10j has a slotted portion 10k extending transversely thereacross adjacent its front edge portion. Said member 10j has a portion 10n extending upwardly and slightly outwardly from its front edge portion. Portions 10m and 10s are identical in structure to portions 10b and 10r. The present modification includes both rods 13 and 14 and their rollers 13a and 14a respectively, as previously described.

The modification of the preceding paragraph is adapted to be used with a roll of adhesive tape which has superposed layers of tape wound thereabout, such as a roll having a layer of adhesive with a cover strip overlying the same. In operation, an end portion of a layer of tape is raised from the roll and the cover strip and the layer of tape are separated for a short distance. Said device is disposed over the periphery of said roll of tape. The cover strip is passed through slot 10k and the layer of adhesive is passed through the space between the front edge portion 10n and the cutting edge portion 10g. Said cover strip is drawn over the edge portion 10n. Both the cover strip and the layer of tape are thereby dispensed simultaneously through said device in a separated condition by one hand of the operator. When a desirable length of tape has been dispensed, both the layer of cover strip and the layer of tape will be pressed downwardly against the cutting edge 10g and they will be simultaneously severed from the roll of tape.

Thus it is seen that I have provided a simply made device for use on a roll of material, such as a roll of adhesive tape. Said device quickly and easily permits the dispensing of a layer of tape of any desired length and provides a cutting edge for severing the same. Said device is easily held in operating position by one hand of the operator while the material or tape from said roll is easily dispensed with the other hand of the operator. Said device has been thoroughly tested and found to be very efficient and practical in use.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A tape dispensing device for use on a roll of adhesive tape comprising a member of sheet material having a top wall having one end portion disposed on the periphery of said roll of tape and extending downwardly and rearwardly tangentially thereto, side walls extending from said top wall and being bent substantially at right angles thereto and lower end portions of said side walls being again bent at substantially right angles to overlap and form an end wall, the lower end of one of said overlapping portions having a flange-like projection engaging the periphery of said roll and the opposite end of said last mentioned overlapping portion forming a cutting edge whereby

a layer of said tape may be drawn under said top wall and over said cutting edge of said end wall to be severed by said cutting edge and said device is positioned on said roll by the front end portion of said top wall and the flange-like projections depending from said end wall.

2. The structure set forth in claim 1, said top wall having a portion being reversely bent to extend substantially parallel thereto and having its terminal end bent up at a slight angle.

3. The structure set forth in claim 1, means connecting said overlapping portions and said cutting edge portion extending over the other overlapping portion a short distance in a direction away from said top wall.

4. A tape dispensing device for use on a roll of tape having superposed layers of material of double thickness wound thereon comprising a member of sheet material having a top wall having one end portion disposed on the periphery of said roll of tape and extending tangentially thereto, said top wall having a slot therein transversely thereof intermediate its end portions, side walls extending downwardly and rearwardly from said top wall and being bent substantially at right angles thereto, and lower end portions of said side walls being bent at substantially right angles to overlap and form an end wall, the lower end of one of said overlapping portions having a flange-like projection engaging the periphery of said roll, and the opposite end of said last mentioned overlapping portion forming a cutting edge whereby a layer of said tape may be drawn under said top wall and separated with one thickness of said layer passing upwardly through said slot and the other thickness of said layer passing under the remainder of said upper wall and both thicknesses being drawn over said cutting edge

to be severed thereby, and said device is positioned on said roll by the front end portion of said top wall and the flange-like projections depending from said end wall.

5. A tape dispensing device for use on a roll of tape having superposed layers of material wound thereon comprising a member of sheet material having a top wall having one end portion disposed on the periphery of said roll of tape and extending tangentially thereto, said top wall having a slot therein transversely thereof intermediate its end portions, side walls extending downwardly and rearwardly from said top wall and being bent substantially at right angles thereto, and the lower end portions of said side walls being bent at substantially right angles and forming an end wall extending across said periphery, the lower end of said end wall having a flange-like projection engaging the periphery of said roll, and the opposite end of said end wall forming a cutting edge whereby a layer of said tape may be drawn under said top wall and passed upwardly through said slot and be drawn over said cutting edge to be severed thereby, and said device is positioned on said roll by the front end portion of said top wall and the flange-like projections depending from said end wall.
